CLAIM

The ornamental design for a towel bar and basket, as shown and described.

DESCRIPTION

FIG. 1 is a perspective view of a towel bar and basket showing our new design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is a perspective view of a second embodiment of a towel bar and basket showing our new design.

FIG. 9 is a front elevation view thereof.

FIG. 10 is a rear elevation view thereof.

FIG. 11 is a left side elevation view thereof.

FIG. 12 is a right side elevation view thereof.

(Continued)

FIG. 13 is a top plan view thereof; and,
FIG. 14 is a bottom plan view thereof.
The broken lines show portions of the design that form no
part of the claimed design.

1 Claim, 8 Drawing Sheets
